EXPLODING TOY

Theodore J. Kuemmerlein and Earl F. Wendt,
Milwaukee, Wis.

Application May 11, 1945, Serial No. 593,290

7 Claims. (Cl. 273—102.1)

1

This invention relates to improvements in exploding toys.

It is a general object of the present invention to provide a toy construction to form a target for a projectile, the toy including mechanism for causing an explosion effect to be produced when the target is hit. While the invention is well suited for use in toy battleships, it has a wide adaptability and may be successfully incorporated in toy tanks or other land vehicles, and in a variety of other miniature objects.

It is recognized that attempts have heretofore been made to produce exploding toy boats, but in these prior structures conventional mousetrap mechanisms have been utilized to create the explosion. This is very objectionable as injury to the hand or finger of a child may readily result from careless handling. In addition to the above, these prior toys have been so constructed that only a single releasing target is provided. Thus, it is not practical for more than one child to shoot at the target at any one time.

It is a general object of the present invention to provide an exploding toy which includes improved explosion producing mechanism so constructed and arranged as to be harmless.

A further object of the invention is to provide a toy of the class described which includes an axially shiftable release member having ends exposed on opposite sides of the toy, said member forming a double target and being responsive to an impact on either end to explode the toy. Thus, two children positioned on opposite sides of the boat or other object may engage in a contest to see which one can hit the target first.

A further object of the invention is to provide an exploding toy having a spring explosion producing device which is simple to set, and which requires little strength on the part of the child.

A further object of the invention is to provide a device as above described having release mechanism which is highly sensitive to an impact on the target proper, requiring but slight axial movement of the release plunger, but which, nevertheless, will not be affected by misdirected hits on other portions of the toy article.

A more specific object of the invention is to provide an exploding toy wherein the explosion is produced by the flexing of a relatively light weight band spring, the outer end of the spring being engageable with a projection on a slideable plunger and being releasable in response to slight axial movement of said plunger.

A still more specific object of the invention is to provide a construction as above described

2

wherein the release is rendered more sensitive by providing for a rolling motion of the plunger immediately after impact.

Other objects of the invention are to provide an exploding toy which is relatively simple and inexpensive in construction, which is simple to assemble, which is neat in appearance, and which is otherwise well adapted for the purpose described.

With the above and other objects in view, the invention consists of the improved exploding toy, and all its parts and combinations, as set forth in the claims, and all equivalents thereof.

In the accompanying drawing, illustrating several embodiments of the invention, in which the same reference numerals designate the same parts in all of the views:

Fig. 1 is a side elevational view of a boat incorporating the invention, the dot-and-dash lines indicating the position of the parts during an explosion;

Fig. 2 is a top view of the hull with the loose portions of the boat removed, part being broken away and shown in section;

Fig. 3 is a sectional view taken on the line 3—3 of Fig. 2;

Fig. 4 is a fragmentary longitudinal vertical sectional view illustrating a modification and taken on the line 4—4 of Fig. 5;

Fig. 5 is a view looking at the bottom of the plunger of the modification in Fig. 4, part of the band spring being illustrated in set position and the lower pin being shown in section and in set position; and

Fig. 6 is a view similar to Fig. 4, illustrating another modification.

Referring more particularly to the drawing, the numeral 10 designates the hull of a battleship. The battleship is being shown and described merely for purposes of illustration, as the invention is well adapted for use in a variety of other miniature objects. The top surface of the hull is formed with a cavity 11 which forms a chamber for the release and explosion producing mechanism. At the rear end of the cavity 11 the hull may be formed with an angular seat 12 to which the end of a band spring 13 is secured as at 14. Various other methods of supporting the end of the spring may be utilized but the method shown eliminates extra parts.

Intermediate the length of the hull is a transverse bore 15. The bore extends entirely through the width of the hull and intersects the cavity 11, as illustrated. Slidable axially in the bore 15 is a releasing plunger 16 having ends 17 and 18.

which reject from opposite sides of the bore and which form oppositely disposed targets.

The plunger must be equipped with suitable means for releasably holding the band spring 13 in the set position of Fig. 3 so that the spring will be released upon axial movement of the plunger. It is desirable to incorporate structure which is highly sensitive so that only a slight axial movement is required. A preferred method of accomplishing this last function is to provide for a slight rolling motion of the plunger immediately after it has been struck. One means for accomplishing this purpose is illustrated in Figs. 2 and 3 where a clip 19 of metal or other suitable material is secured to the upper side of the plunger by a nail 20. The clip has a spring engaging lug or extension 21 which projects from one side of the plunger, and also an extension 22 which projects from the opposite side. The extension 22 is preferably pointed as is illustrated in Fig. 2, to render the device more sensitive, and is adapted to engage over the head of a brad 23, or similar member, to hold the plunger against rolling motion when it is in set position.

In use of the toy, it is preferred to provide a wooden or metal projectile which can be shot by spring mechanism in a toy submarine or gun. If either of the ends 17 or 18 of the release plunger 16 is hit, the plunger will be moved axially a sufficient distance to push the setting extension 22 off of the head of the brad 23. This will immediately allow the plunger to roll to the dot-and-dash line position of Fig. 3 to release the band spring 13. The latter will flex forceably from the full line position of Fig. 3 to the dot-and-dash line position therein, and will cause any loose parts superimposed on the hull to fly into the air in the manner shown in Fig. 1.

When the toy is a battleship as is illustrated, the loose parts may comprise a relatively flat board 24 forming a deck and cover for the cavity 11. The board 24 may support other loose objects, such as the guns 25, smoke stacks 26, and smoke stack support 27.

In the modification illustrated in Fig. 6, instead of utilizing the clip 19, one side of the plunger may be notched as at 28 and the band spring 13 may be made slightly longer to engage with the notch. Projecting from the other side of the plunger is a suitable projection 29 which corresponds to the member 22 of the form of invention shown in Fig. 3, and which is cooperable with the brad 23.

In the form of the invention illustrated in Figs. 4 and 5, the lower side of the plunger is longitudinally grooved as at 30, and the rear side of the plunger is grooved as at 31. Angular grooves 32 and 33 intersect the groove 30 and are arranged in V-shaped formation as illustrated in Fig. 5. Projecting upwardly from the lower side of the plunger bore 15 is a brad or other suitable member 34.

When the parts are set they are in the position illustrated in Figs. 4 and 5, with the brad head engaging the short portion 30' of the groove 30, and with the end of the band spring engaged in the rear groove 31. When one end of the plunger 16' is struck, the plunger will be moved axially a sufficient distance to cause the brad to register with the angular groove 33. This will then allow the plunger to roll and release the end of the band spring 13. When the other end of the plunger is struck, the plunger will move axially a sufficient distance to cause the brad to register with the other angular groove 32. This will

cause a similar rolling movement and a resulting release of the band spring.

It is apparent from the above that in all forms of the invention a blow on either of the ends 17 or 18 of the release plunger or target will cause axial releasing movement. Although only slight movement is required for such release it is, nevertheless, clear that the tension in the cocked spring 13 is sufficient to maintain the parts firmly in set position, unless the plunger is actually struck. A misdirected hit on other portions of the hull will not cause an explosion.

It is also clear from the above description that all of the parts are extremely simple in construction, and that the assembly work during manufacture consists merely in driving the nails 14 and 20 and in inserting the brad 23 or 34.

Various changes and modifications may be made without departing from the spirit of the invention, and all of such changes are contemplated as may come within the scope of the claims.

What we claim is:

1. In an exploding toy having a body portion forming a base and having at least one body part removably positionable in assembled relationship with said base, a releasable band spring engageable upon release with said loose body part to forceably displace the latter, a plunger mounted transversely of said base for axial and rolling movement, means on said plunger for engagement with the band spring for releasably holding the latter in set condition when the plunger is in one position of rotatable adjustment, and means for preventing rolling movement of the plunger when the latter is in one position of axial adjustment and permitting said rolling movement when said plunger is axially displaced from said position, at least one of the ends of said plunger being exposed to an external blow to move the plunger out of said position of axial adjustment and release the spring actuated means.

2. In an exploding toy having a body portion forming a base and having at least one body part removably positionable in assembled relationship with said base, a releasable band spring engageable upon release with said loose body part to forceably displace the latter, a plunger mounted transversely of said base for axial and rolling movement, a relatively narrow extension projecting from the plunger for engagement with the spring actuated means when the plunger is in a predetermined position of rotatable and axial adjustment, and means for preventing rolling movement of the plunger when the latter is in one position of axial adjustment and permitting said rolling movement when said plunger is axially displaced from said position, at least one of the ends of said plunger being exposed to an external blow to move the plunger out of said position of axial adjustment and release the spring actuated means.

3. In an exploding toy having a body portion forming a base and having at least one body part removably positionable in assembled relationship with said base, releasable spring actuated means engageable upon release with said loose body part to forceably displace the latter, a plunger mounted transversely of said base for axial and rolling movement and having a recess 70 which is engageable with the spring actuated means to releasably hold the latter in set condition when the plunger is in one position of rotatable adjustment, and means for preventing rolling movement of the plunger when the latter is in one position of axial adjustment, at least one

of the ends of said plunger being exposed to an external blow to move the plunger out of said position of axial adjustment and release the spring actuated means.

4. In an exploding toy having a body portion forming a base and having at least one body part removably positionable in assembled relationship with said base, releasable spring actuated means engageable upon release with said loose body part to forceably displace the latter, a plunger mounted transversely of said base for axial and rolling movement, means on said plunger for engagement with the spring actuated means to releasably hold the latter in set condition when the plunger is in one position of rotatable adjustment, roll-preventing means on the plunger, and a pin projecting upwardly from the base and engageable with said roll-preventing means when the plunger is in one position of axial adjustment, at least one of the ends of said plunger being exposed to an external blow to move the plunger out of said position of axial adjustment and release said spring actuated means.

5. In an exploding toy having a body portion forming a base and having at least one body part removably positionable in assembled relationship with said base, releasable spring actuated means engageable upon release with said loose body part to forceably displace the latter, a plunger mounted transversely of said base for axial and rolling movement, means on said plunger for engagement with the spring actuated means to releasably hold the latter in set condition when the plunger is in one position of rotatable adjustment, said plunger having a longitudinal groove portion therein and having a second groove portion extending transversely of the longitudinal groove portion and communicating with the latter, and a pin engageable with said longitudinal groove portion to prevent rolling movement of the plunger, said pin being registerable with the second groove portion in response to axial movement of the plunger to permit rolling movement and release of the spring actuated means.

6. In an exploding toy having a body portion forming a base and having at least one body part removably positionable in assembled relationship with said base, releasable spring actuated means engageable upon release with said loose body part to forceably displace the latter, a plunger mounted transversely of said base for

axial and rolling movement and having opposite ends exposed on both sides of the base, means on said plunger for engagement with the spring actuated means to releasably hold the latter in set condition when the plunger is in one position of rotatable adjustment, said plunger having a longitudinal groove portion therein and having other spaced groove portions extending transversely of the first groove portion and communicating with the latter, and a pin engageable with said longitudinal groove portion to prevent rolling movement of the plunger, said pin being registerable with one or the other of said spaced groove portions in response to a blow on either end of the plunger to permit rolling movement and release of the spring actuated means.

7. In an exploding toy having a body portion forming a base and having at least one body part removably positionable in assembled relationship with said base, releasable spring actuated means engageable upon release with said loose body part to forceably displace the latter, a plunger mounted transversely of said base for axial and rolling movement and having opposite ends exposed on both sides of the base, means on said plunger for engagement with the spring actuated means to releasably hold the latter in set condition when the plunger is in one position of rotatable adjustment, said plunger having a longitudinal groove portion therein and having a pair of spaced converging grooves extending substantially transversely of the first groove portion and communicating with the latter, and means engageable with said longitudinal groove portion to prevent rolling movement of the plunger, said means being registerable with one or the other of said spaced groove portions in response to a blow on either end of the plunger to permit rolling movement and release of the spring actuated means.
